UNITED STATES PATENT OFFICE.

WILLIAM VOGEL, OF NEW YORK, N. Y.

FLASH PISTOL.

Application filed August 25, 1925. Serial No. 52,293.

To all whom it may concern:

Be it known that I, WILLIAM VOGEL, a citizen of the United States, residing at New York, in the county of New York and 5 State of New York, have invented certain new and useful Improvements in Flash Pistols, of which the following is a specification.

This invention relates to flash light or 10 analogous mechanisms, and has particular reference to devices used by commercial photographers and usually known as flash pistols.

Among the objects of the invention are to 15 provide an apparatus of the character indicated that will be simple to construct, easy and safe to operate, and durable in use; to insure absolute reliability in firing the charge of flash powder and illumination of 20 the scene to be pictured; to provide for proper adjustment of the camera actuator and hence suitable timing of the shutter mechanism with respect to the ignition of the powder; and to provide a safe and convenient receptacle or magazine for the percussion caps or primers. 25

With the foregoing and other objects in view the invention consists in the arrangement and combination of parts hereinafter 30 described and claimed, and while the invention is not restricted to the exact details of construction disclosed or suggested herein, still for the purpose of illustrating a practical embodiment thereof reference is had to 35 the accompanying drawings, in which like reference characters designate the same parts in the several views, and in which—

Figure 1 is a side elevation showing a preferred embodiment of my invention in normal idle or fired position. 40

Fig. 2 is a similar view in cocked position, ready to fire.

Fig. 3 shows the hammer approaching the firing position and about to release the shutter mechanism carrier. 45

Fig. 4 shows the next step with the carrier released and the shutter actuator about to impinge against the adjustable abutment.

Fig. 5 is a sectional detail on the line 5—5 50 of Fig. 1.

Fig. 6 is a fragmentary view of the handle with the magazine cover partially open.

Referring now more specifically to the drawings I show at 10 a rigid frame made 55 preferably as a flat plate or bar of metal and of uniform width. This frame has secured

to its laterally turned upper end 11 an open topped flash pan 12 having a flash hole 13 formed through its bottom. At the lower end the frame is provided with a cavity 14, which together with the relatively fixed and movable handle pieces 15 and 16, respectively, forms a receptacle or magazine for the percussion caps or primers C. The cover piece 16 is held shut normally by the tightening of a thumb nut 17 against the slotted end thereof.

The primer to be fired is held against the bottom of the pan 12 and spanning the hole 13, the means shown for this purpose being a flap 18 hinged at 19 and urged normally against the pan bottom by a spring 20. The primer is easily placed as a result of the lifting of the flap away from the pan and against the force of the spring. 75

The haminer 21 is made as a unitary part of a shank member or plunger 22 slidable along one side of the plate 10 and lengthwise thereof, being urged normally upward by virtue of the contractile main spring 23, anchored at one end on a lug 24 and at the other end upon a hook 25 attached to the pan, and adapted to be drawn downward into cocked position and against the force of the spring 23 by manipulation at the finger piece 26. This member is guided and confined for movements in parallelism with the frame by means of guides 27 extending through slots 28 in the plunger. The striking end or portion of the hammer registers 90 with the hole 13 in firing position and hence while exploding the primer causes a flash therefrom to pass through the hole and ignite the powder in the pan for its usual purpose. 95

The plunger has formed upon its inner edge remote from the finger piece 26 a cam or lug 29 bounded at its lower larger end by a shoulder 31, and spaced below it is a shoulder 32 facing upward toward the shoulder 31. 100

The carrier 33 aforesaid is shown as a substantially flat plate formation, having a slot 34 extending lengthwise thereof for confining it for position and movements along the frame parallel to the plunger, it being so confined by fixed guides 35 extending through the slot. At the upper end the carrier is provided with a laterally turned fork or yoke 36 which carries or to which is clamped the tubular actuator 37 for the camera shutter (see Fig. 4) and within 105 110

which is the push rod or wire 38 projecting upward. A contractile spring 39 is anchored at one end at a hook 40 and at the other end to the carrier at 41, and this spring 5 tends to draw the carrier upward toward an abutment 42 adjustable up and down along the frame at a slot 43, a set screw or thumb nut serving to lock the abutment at the proper place to allow a suitable gap 10 between it and the wire 38 in cocked position and whereby the actuation of the shutter mechanism may be suitably adjusted or timed with relation to the firing of the powder.

15 On the side or edge adjacent to the plunger the carrier is provided with an upwardly projecting hook-shaped lug 44 lying in the path of and normally in contact with the shoulder 31, whereby when the 20 plunger is drawn manually downward for cocking the hammer the carrier follows it, both springs 23 and 39 being put simultaneously under tension. See Fig. 2.

Pivoted to the frame 10 at 45 and between the carrier and plunger is a dog 46, so placed as to engage over or lie in the path of a shoulder 47 on the carrier when the device is cocked. A spring 48 bearing against the tail piece 49 tends to hold the dog in cooperation with said shoulder 47.

A trigger is provided in the nature of a bell crank lever 50, pivoted at 51 conveniently near the handle and whose upper end 52 is adapted to hook over the shoulder 32 to hold releasably the plunger in set or cocked position, by virtue of a contractile spring 53 having its ends anchored at a fixed point 54 on the frame and a lug 55 on the trigger.

40 With the pan suitably charged and primed, from the position in Fig. 2 when the trigger is released from the shoulder 32 the hammer, being set free, as in Fig. 3, speeds upward toward the primer, the carrier being momentarily retained and so retarded by co-operation between the dog 46 and the shoulder 47, but just before the hammer reaches firing position the cam 29 strikes or wipes against the tail piece 49 and releases the dog from the carrier shoulder 47 and so sets the carrier free to be carried upward by virtue of the spring 39, see Fig. 4, causing the functioning of the camera actuator, in co-operation with 45 the abutment 42, soon after the ignition of the charge. The lower the adjustment of the abutment the sooner will the shutter be

actuated in relation to the firing of the powder. Hence the actuating mechanism comprises two main sliding members movable together in one direction as a unit and in succession or separately in the other direction. Furthermore, while the hammer may be described as having a fixed time of operation as regards its release from the trigger, the carrier is retarded somewhat in its throw, and by adjustment of the abutment (which after adjustment may be thought of as a relatively fixed member) the time of actuation of the shutter mechanism will be variable and determined so as to take place at a suitable time after both the hammer and carrier are projected. The actuator tube 37 may of course be adjusted relatively to the yoke 36 to correspond with the vertical adjustments of the fixed abutment 42.

I claim:

1. In a flash pistol, the combination of a frame, a powder pan attached thereto and having a priming hole, a reciprocating hammer slideable along the frame toward and from said hole, means to hold a primer at the hole in the path of the hammer, means to project the hammer forcibly against the primer to explode it, and shutter actuating mechanism timed for proper functioning with respect to the firing of the primer, said shutter actuating mechanism comprising an abutment, a tubular actuator, and means to carry the tubular actuator into contact with said abutment for operating the camera.

2. A device as set forth in claim 1 in which the shutter mechanism includes a carrier for the tubular actuator and means to set it into motion subsequently to the actuation of the hammer, the abutment being adjustable toward or away from the means carrying the actuator whereby the precise timing of the camera can be varied.

3. Mechanism as set forth in claim 1 in which the hammer and the carrier are confined for movement along parallel paths and the connections between them include a dog pivoted on a fixed pivot between them, the dog serving to hold momentarily the carrier till after the hammer starts on its movement and releasable by the hammer as the hammer approaches the limit of its independent movement.

In testimony whereof I affix my signature.

WILLIAM VOGEL.
